VENT PLUG FOR A CONTAINER CONTAINING
A LIQUID

Joseph Lester Woodbridge, Philadelphia, Pa., assignor to The Electric Storage Battery Company, Philadelphia, Pa., a corporation of New Jersey

Application May 26, 1931. Serial No. 540,986

5 Claims. (Cl. 220—44)

The object of my invention is a vent plug for a container containing liquid such as a storage battery containing electrolyte. My improved vent plug consists of a valve seat, a supporting ledge beneath said valve seat, a weighted member supported on said ledge and having orifices therein, and a valve member supported on said weighted member and adapted to close said valve seat when the container is tilted.

10 For a further exposition of my invention reference may be had to the annexed drawing and specification at the end whereof my invention will be specifically pointed out and claimed.

In the drawing there is shown a vertical cross section through my device with parts in side elevation. The drawing shows a hollow vent plug 1 screwed into the opening of the cover 2 of a storage battery cell generally indicated at 3. At the bottom of the vent plug there is an internal ledge 4, upon which rests a weighted member 5. The member 5 has a cup like depression at the top, in the center of which projects a conical pin 7. On this conical pin rests a hemispherical valve member 8, having on its underside a conical cavity into which the pin 7 projects for supporting the member 8, leaving it free to rock about the point of the pin 7. Near the bottom of the vent plug 1 is a conical member 9 with a central orifice 10 opening from the interior of the vent plug into the top of the cell and provided at its bottom with spherically surfaced valve seat 11 adapted to cooperate with the valve member 8 to close the orifice 10 when the valve member 8 is raised to bear upon the valve seat 11. The vent plug 1 is provided with a cap 12 having a depending vent duct 13 to permit the escape of gas from the cell during normal operation. The upper cup shaped portion of the weighted member 5 is provided with openings 14 to permit gas to escape from the cell and to drain back any liquid from the vent plug when the cell is in its normal upright position.

When the cell is standing in its normal upright position, the parts of the vent plug will be located as shown in the drawing with the valve member 8 out of contact with the valve seat 11, permitting the gas generated from the cell to escape. If the cell is tilted to a certain angle in any direction, the weighted member 5 will rock about a point of contact between the lip 6 and the ledge 4, bringing the valve member 8 into contact with the valve seat 11, thus closing the orifice 10 and preventing liquid from escaping from the cell. If a few drops of liquid should escape into the upper part of the vent plug

1, it will be trapped in the space around the vent duct 13 and will not pass out but will be drained back into the cell when the cell is restored to its normal position.

In the normal position of the parts shown in the drawing, the tip of the conical point 7 is slightly below the plane of the ledge 4, and in the position with the cell tilted, this tip will be slightly above the plane of the ledge 4, the travel of the tip of the point 7 being substantially axial with respect to the vent plug. By supporting the spherical valve member 8 as shown, it is free to rock slightly on the tip of the point 7 and therefore seat accurately on the valve seat 11.

I do not intend to be limited in the practice of my invention save as the scope of the prior art and of the attached claims may require.

I claim:

1. In a non-spill vent plug for a closed container containing liquid, a valve seat defining an orifice opening from the vent plug into the container, an annular supporting ledge below the valve seat, a weighted member having an annular lip adapted to be supported on said ledge and having a centrally located supporting pin and having an opening therein providing a drain beneath said valve seat when said container is in normal position, and a valve member supported on said pin normally out of contact with the valve seat and adapted to be brought into contact therewith by the rocking of the weighted member on the supporting ledge caused by the tilting of the container.

2. In a non-spill vent plug for a closed container, a valve seat defining an orifice opening from the vent plug into the container, an annular supporting ledge below the valve seat, a weighted member having an annular lip adapted to be supported on said ledge and having an orifice therethrough, a supporting pin projecting from the upper surface of said weighted member to a point just beneath the plane of said supporting ledge, a valve member supported on said pin normally out of contact with the valve seat and adapted to be brought into contact therewith by the rocking of the weighted member on the supporting ledge caused by the tilting of the container, and a wall having a vent therein projecting downward into the interior of said vent plug.

3. In a non-spill vent plug for a closed container containing liquid, a valve seat defining an orifice opening from the vent plug into the container, an annular supporting ledge below the valve seat, a weighted member having an an-

nular lip adapted to be supported from said ledge, a supporting pin projecting from the upper surface of said weighted member to a point just beneath the plane of said supporting ledge, 5 and a valve member supported on said pin normally out of contact with the valve seat and adapted to be brought into contact therewith by the rocking of the weighted member on the supporting ledge caused by the tilting of the 10 container.

4. In a non-spill vent plug for a closed container containing liquid, a valve seat defining an orifice opening from the vent plug into the container, an annular supporting ledge below the 15 valve seat, a weighted member having an annular lip adapted to be supported on said ledge, a supporting pin projecting from the upper surface of said weighted member to a point just beneath the plane of said supporting ledge, and a 20 valve member having a conical cavity in its under surface supported on said pin at the apex of said conical cavity and normally out of contact with the valve seat and adapted to be

brought into contact therewith by the rocking of the weighted member on the supporting ledge caused by the tilting of the container.

5. In a non-spill vent plug for a closed container containing liquid, a valve seat defining an orifice opening from the vent plug into the container, an annular supporting ledge below the valve seat, a weighted member having an annular lip adapted to be supported from said ledge, 80 and a valve member adapted to be supported by said weighted member beneath and normally out of contact with the valve seat and adapted to be brought into contact therewith by the rocking of the weighted member on the supporting ledge caused by the tilting of the container, the 85 supporting contact between the weighted member and the valve member being in the form of a pin projecting from one of said members resting at the apex of a cavity in the other, said contact being located just beneath the plane of said 90 annular lip.
